GALLSTONE SOLUBILIZER

CROSS REFERENCES TO RELATED
APPLICATIONS

The present application is a continuation in part of application Ser. No. 237,918 filed Mar. 12, 1972, now abandoned, which is hereby incorporated by reference.

BACKGROUND OF THE INVENTION

Bile contains large amounts of organic and inorganic components which are easily crystallized. Such components in the bile are crystallized into gallstone in some instances. The greater part of the crystal grows gradually on the wall of the gallbladder or bile duct. Gallstones in bile are various in size and number. They are in the form of sand grains, large lumps or relatively small grains (2-10 in number). The gallstones comprise various constituents which may be divided roughly into three groups of (1) fatty acid calcium stones, (2) bilirubin stones and (3) cholesterol stones.

Chololithiasis without any subjective symptom causes no particular trouble and the stone in such a case is called a "silent stone." However, if a gallstone is caught at the outlet of the gallbladder thereby causing abnormal contraction of the gallbladder, or if the discharged gallstone is caught in the bile duct thereby causing bile duct convulsion, the patient feels acute pain.

For the treatment of chololithiasis, it is necessary to remove the gallstones completely. The removal of gallstones without surgery before subjective symptoms appear is the most preferable treatment. However, the method of such a treatment has not yet been developed. Although gallstones can be removed thoroughly by a surgical operation before subjective symptoms appear, this is not recommended generally, since the patient sometimes feels no pain throughout his life in spite of the presence of gallstones.

Usually, a patient having chololithiasis is subjected to cholangiography with a contrast medium, when he has subjective symptoms, to confirm the position of gallstones and then the gallstones are removed by a surgical operation. However, sometimes small stones in the bile duct are missed during the operation. Also, new gallstones are often again formed after the operation. Such cases are not rare and those stones are called "residual stones." The greatest problem in the treatment of chololithiasis is the residual stone. At present, surgery must be repeated again if any residual stone is found.

THE PRIOR ART

Chololithiasis treatments include internal treatment, surgical treatment and combined internal and surgical treatments.

The internal treatment includes the following methods:

1. Lyon's method:

A duodenal sound is used. Magnesium sulfate is infused through the sound to react on the duodenal papilla whereby the sphincter of Oddi is loosened. Consequently, bile flows out thereby removing gallstones.

2. Treatment with cholagogues:

A cholagogue is reacted on parenchymal liver cells to increase secretion of bile thereby discharging the gallstones. As the cholagogues, there are used, for example, dehydrocholic acid, ursodesoxycholic acid,

α -oxy- α -(8-fluoranthene) butyric acid, p-tolylmethylcarbinol, 1-phenylpropanol and Rowachol.

3. Treatment with cholecystokinetics:

A cholecystokinetics is used to loose the sphincter of Oddi and sometimes also to cause contraction of the wall of the gallbladder simultaneously, whereby bile is discharged. As the cholecystokinetics, there are used, for example, cholecystokinin, pituitrin, atenin, butter, egg yolk, peptone, cow's milk and magnesium sulfate.

The surgical treatments include the following methods:

1. Drainage of the biliary tract.
2. Anastomosis of the bile duct and duodenum.
3. Resection of liver.

15 In all of the above cases, the gallbladder is removed.

The combined internal and surgical treatments are carried out for removing residual stones after a surgical operation. The combined treatment comprises first infusing an organic solvent such as chloroform or chloro-

20 form/ether mixture through a drain inserted in ductus choledochus to solubilize the residual stone [Pribram, B.O.C. Lancet, 1, 1311 (1939) and Best, Arch. Surg., 67, 839 (1953)]. This treatment may comprise infusion of a chelating agent such as a polyphosphate, for example sodium hexametaphosphate, to solubilize the gallstone [Hisatsugu, Igaku Kenkyu (Acta Medica), 29, 1773 (1959)].

25 In addition, some mechanical methods have been tried, for example, an elevating pressure has been added to the bile duct to discharge the gallstone adhering to the inner wall of the duct [Dardik, Digestive Diseases, 16, 321 (1971)].

Thus, various treatments have been tried for chololithiasis. However, by the conventional internal treatments, permanent healing is almost impossible, though

30 some gallstones can be removed. By the surgical treatments, on the other hand, the problem of residual stones cannot be solved, though gallstones can be removed completely from the part of incision and, therefore, permanent healing cannot be attained by this

35 method. Under the above circumstances, combined internal and surgical treatments have been tried in which residual stones which remain after a surgical operation or which are formed thereafter are removed in various manners. However, if an organic solvent is used, a toxic

40 effect is exhibited and, in addition, solubility of the gallstone in the solvent is poor. If a polyphosphate is used, a disadvantage is that if the stone is a cholesterol stone it cannot be removed at all, though fatty acid calcium stones can be so removed. The method of increasing

45 mechanically pressure in the bile duct is dangerous and, therefore, it cannot be carried out safely and easily. Although residual stones can be removed surgically, a search for the gallstone in the bile duct is particularly difficult and repetition of the surgical operation is extremely difficult and is sometimes impossible, since the first operation sometimes causes adhesion of the organs.

OBJECT OF THE INVENTION

60 It is an object of the present invention to overcome the deficiencies of the prior art, such as indicated above.

Another object is to provide for improved gallstone removal.

65 Another object of the present invention is to provide a gallstone solubilizer which solubilizes gallstones completely.

Another object of the invention is to provide a gallstone solubilizer which is directly infused, after a surgical operation for cholelithiasis, through a drain inserted in the bile duct to remove residual stones.

Still another object of the invention is to provide a gallstone solubilizer which is directly infused through a drain inserted in the bile duct of a patient of cholelithiasis to solubilize gallstones completely.

A further object of the invention is to provide a clear gallstone solubilizer which is stable for a long period of time.

These and other objects will be more apparent from the following detailed description of embodiments of the invention:

DESCRIPTION OF THE INVENTION

The present invention relates to a gallstone solubilizer comprising a member selected from the group consisting of monoterpenes, sesquiterpenes, essential oils containing those terpenes and mixtures thereof. Particularly, the invention relates to a gallstone solubilizer comprising a mixture of (a) a member of the group consisting of monoterpenes, sesquiterpenes, essential oils containing those terpenes and mixtures thereof and (b) a member of the group consisting of nonionic surfactants and mixtures thereof. Preferably, the mixture also contains (c) a stabilizer selected from the group consisting of alcohols, amides, phospholipids, esters, water and mixtures thereof.

The preferable solubilizer in accordance with the present invention comprises 99.8 - 70% (W/V) of limonene, 0.1 - 15% (W/V) sorbitan monolaurate, sorbitan monooleate or polyoxyethylene sorbitan monooleate having about 20 moles of oxyethylene, and 0.1 - 15% (W/V) ethanol or water.

By using the gallstone solubilizers of the present invention, cholesterol stones which are difficult to solubilize according to conventional methods can be solubilized completely within a short period of time. Of course, the gallstone solubilizers also solubilize bilirubin stones and fatty acid calcium stones and, therefore, if the gallstone solubilizers of the present invention are used after a surgical operation or directly, permanent healing of cholelithiasis is possible.

Active ingredients for solubilizing gallstones in the solubilizers of the invention are terpenes, particularly, monoterpenes and sesquiterpenes. They are used solely or in the form of mixture. Numerous essential oils may be used directly, since they contain large quantities of monoterpenes and sesquiterpenes. The essential oils may be used also in the form of a mixture with a monoterpene or sesquiterpene.

The monoterpenes are, for example, myrcene, ocimene, linalool, geraniol, nerol, citronellol, artemisia ketone, citral, citronellal, linalyl acetate, limonene, dipentene, terpinolene, phellandrene, terpinene, sylvestrene, terpineol, perillaldehyde, carvone, pulegone, piperitone, menthone, 1,8-cineole, 1,4-cineole, sabinene, pinene and umbellulone, preferably limonene.

Sesquiterpenes are, for example, farnesol, nerolidol, bisabolene and zingiberene.

Though the above-mentioned monoterpenes and sesquiterpenes include their stereoisomers and optical isomers, they may be used in the form of mixtures directly separated from natural materials without any further treatment. Of course, pure stereoisomers and optical isomers may also be used.

Essential oils containing a monoterpane or sesquiterpene are, for example, neroli oil, Kuromoji oil, opopanax oil, lemon-grass oil, perilla oil, caraway oil, star anise oil, lemon oil, lavender oil, turpentine oil, citronella oil, bergamot oil, eucalyptus oil, pennyroyal oil and ginger oil.

The monoterpenes, sesquiterpenes and essential oils containing those terpenes solubilize or directly break up gallstones at a surprisingly high speed. This is proved by the following experiments:

Gallstone Solubilization Test - 1

(Preparation of cholesterol tablets)

Cholesterol (special grade) in an amount of 100mg/tablet was processed in a tablet-making machine to obtain tablets of diameter 7 mm and hardness 6-7 Kg/mm². The following tests were carried out by using the tablets as artificial cholesterol stones. (Solubilization test)

Five milliliters of an essential oil or a terpene were charged in a 20 ml Erlenmeyer flask which were then mixed with the above mentioned cholesterol tablet and the whole was shaken in a water bath at 37°C. Solubilization time indicates a time required for the complete solubilization of the tablet.

Solubilization time is represented as follows:

Within 60 minutes: +++

Within 120 minutes: ++

Within 180 minutes: +

Longer than 180 minutes: -

Following tables 1, 2 and 3 show the results of solubilization tests of monoterpenes, sesquiterpenes, essential oils and mixtures thereof on artificial cholesterol stones.

If a monoterpenes, a sesquiterpene or an essential oil containing such a terpene is brought into contact with a gallstone, it solubilizes the gallstone quickly. However, gallstones in the human gallbladder or bile duct are surrounded by a fairly large quantity of bile.

In the solubilization of gallstones in a human body with a monoterpenes, a sesquiterpene or an essential oil containing such a terpene, bile must be discharged from the body or it must be washed away therefrom into the intestines before infusion of the solubilizer in order to facilitate the contact thereof with the stone and thereby to facilitate the solubilization. Though the solubilization can be carried out by direct infusion of the solubilizer without effecting such a pre-treatment, solubilization time is prolonged in such a case, since bile is a hindrance to the solubilization.

According to the present invention, gallstone in bile can be solubilized at a surprisingly high velocity by using a monoterpenes a sesquiterpene or an essential oil containing such a terpene incorporated with a nonionic surfactant.

The gallstone solubilizer of the present invention is prepared by mixing 99.8-85% (W/V) of a member of the group consisting of monoterpenes, sesquiterpenes, essential oils containing those terpenes and mixtures thereof with 0.1-15% (W/V) of a member of the group consisting of nonionic surfactants and mixtures thereof. Preferred amount of the nonionic surfactant is in the range of 0.2-5.0% (W/V).

Clear gallstone solubilizer in the form of homogeneous solution is obtained by heating the mixture to a temperature of 10°-150°C, preferably 20°-70°C, preferably 20°-70°C under stirring.

- 5 The nonionic surfactants used in the present invention are, for example, glyceryl monooleate, glyceryl monostearate, sorbitan monolaurate, sorbitan monooleate, sorbitan monostearate, sorbitan trioleate, sorbitan monopalmitate, sorbitan tristearate, sorbitan sesquioleate, polyoxyethylene sorbitan monooleate such as Polysorbate 80 having 20 moles of oxyethylene, polyoxyethylene sorbitan monolaurate, polyoxyethylene sorbitan monostearate, polyoxyethylene sorbitan trioleate, polyoxyethylene sorbitan monopalmitate, polyoxyethylene sorbitan tristearate, polyoxyethylene stearate, polyoxyethylene castor oil and polyoxyethylene hydrogenated castor oil, preferably sorbitan monolaurate, sorbitan monooleate or Polysorbate 80.

In the solubilization of gallstone in a human body, the gallstone solubilizer of the present invention containing a nonionic surfactant is easily emulsified together with bile and thereby brought into contact with the stone to solubilize the stone at a surprisingly high velocity. This is apparent from the following emulsification test on bile and gallstone solubilization test.

Table 4 shows the results of the emulsification test of mixtures of a terpene or an essential oil and a nonionic surfactant on artificial bile or human bile. Table 5 shows the results of the test of solubilization of artificial cholesterol stones with the gallstone solubilizers.

Emulsification Test on Bile

Seven parts of a gallstone solubilizer of the present invention are added to three parts of human bile or isotonic sodium chloride solution (as artificial bile). The whole is shaken vigorously and allowed to stand for five minutes. Phase separation of the mixture was examined.

40 The results were shown as follows:

Non-separation: ++

Slight separation: ++

Considerable separation: ±

Gallstone Solubilization Test

Solubilizing powers of the gallstone solubilizers of the present invention for artificial cholesterol stones mixed with human bile were examined. 15 Milliliters of a mixture comprising 5-9 parts of the solubilizer and 1-5 parts of human bile were charged in a 30 ml Erlenmeyer flask. An artificial cholesterol stone was added to the mixture and the whole was shaken in a water bath at 37°C. Solubilization time indicates a time required for complete disappearance of the whole artificial stone.

P.O.E. = Polyoxyethylene

According to the present invention, it is possible to solubilize gallstone readily by using monoterpenes, sesquiterpenes and essential oils containing those terpenes mixed with one or more nonionic surfactants in the form of a mixture. However, the gallstone solubilizer comprising a more mixture of those components is unstable and causes separation of the liquid into layers, turbidity of the clear liquid or formation of precipitates during a long period storage or due to climatic change.

These disadvantages have been eliminated by incorporating a stabilizer in the gallstone solubilizer. The stabilizer is selected from the group consisting of alcohols, amides, phospholipids, esters, water and mixtures thereof. The stabilizers are, for example, ethyl alcohol, lauryl alcohol, myristyl alcohol, stearyl alcohol, glycerol, ethanol, isopropyl alcohol, ethylene glycol, propylene glycol, triethylene glycol, methyl cellosolve, butylene glycol, dimethylacetamide, diethylacetamide, lecithin, isopropylidene glycerol, ethyl oleate, isopropyl myristate, benzyl benzoate, ethyl lactate, water and mixtures thereof, and preferably ethanol or water.

The clear, stable gallstone solubilizers of the present invention thus comprise 99.8-70% (W/V) of a member selected from the group consisting of monoterpenes, sesquiterpenes, essential oils containing those terpenes or mixtures thereof, 0.1-15% (W/V) of a member selected from the group consisting of nonionic surfactants and mixtures thereof and 0.1-15% (W/V) of a stabilizer. The stabilizer is preferably in a quantity in the range of 0.5-7.0% (W/V).

Thus resulting mixture is heated to 10°-150°C, preferably 20°-70°C under stirring to obtain homogeneous solution. Thus, clear, stable gallstone solubilizer is obtained. Tests were carried out on the effects obtainable by the solubilizers. Table 6 shows the results of emulsification tests for bile and also the results of tests on solubilization of gallstone. It is apparent from the results that the gallstone solubilizers of the present invention

40

are stable and readily miscible with bile and that they have excellent gallstone solubilizing effects.

5 **Tests for Effect of Stabilizer**
(Method of stabilization test)

The solubilizers were allowed to stand in a refrigerator at 5°C for 12 hours, then filtered, again allowed to stand for an additional 72 hours and stability was examined.

10 The stabilities are shown as follows:

Stable: ++
Substantially stable: +
Unstable: -

15 **(Method of emulsification of bile)**

Seven parts of a solubilizer were added to three parts of human bile or isotonic sodium chloride solution (as artificial bile). The whole was shaken violently for one minute. After allowing to stand for five minutes, the degree of separation was examined.

20 The results are shown as follows:

Non-separation: +++
Slight separation: ++
Considerable separation: +
"Complete" Separation: -

25 **(Method of gallstone solubilization test)**

In an Erlenmeyer flask, 30 ml of a mixture comprising 5-9 parts of a gallstone solubilizer and 1-5 parts of human bile were charged. Artificial cholesterol stone was added to the mixture and the whole was shaken in a water bath at 37°C. Solubilization time indicates a time required for complete disappearance of the whole artificial cholesterol stone.

30 Solubilization time:

Within 30 minutes: ++
Within 60 minutes: +
Longer than 60 minutes: -

P.O.E. Polyoxethylene

The gallstone solubilizers of the present invention are used by directly infusing them into the human body through a drain inserted in the bile duct and, after the solubilization of the gallstone, the solubilizers are excreted into the duodenum. Therefore, if the solubilizers were to show any toxicity, a serious problem would occur in the human body. Toxicities of representative terpenes and nonionic surfactants used in the gallstone solubilizers were examined. The results of the test are shown in Tables 7 and 8.

Toxicity Test

Test samples were given perorally to mice and rats.

Table 7

No.	Terpene	LD ₅₀ (ml/kg P.O.)
1.	Linalool	3.9
2.	Menthone	1.8
3.	1,4-Cineole	2.4
4.	Terpinolene	4.4
5.	Carvone	5.1
6.	Limonene	4.3
7.	Myrcene	8.3
8.	Linalyl acetate	8.5

Then, the gallstone solubilizers of the present invention were tested by using pigs. It was confirmed that the gallstones are dissolved completely.

35

A pig in the experiments weighing 50 kg was subjected to median incision under general anesthesia. Normality of the internal organs in the abdominal cavity was confirmed. The liver was pushed aside to expose the gall-bladder. Upon effecting a small incisional cut, a large human cholesterol stone (2.1 g) was placed in the gall bladder. A Nelatone's tube was inserted therein and fixed thereto and also to the peritoneum. Non-leakage of the bile through the Nelatone's tube was confirmed and the tube was buried within the abdominal wall. The abdominal wall was sutured to complete the operation.

One week after the operation a small incisional cut of the skin was effected and the buried Nelatone's tube was exposed. A solubilizer of Example 6 infra was infused through the tube once a day for two days in a quantity of 60 cc. each.

A day after the completion of the infusion, disappearance of the gallstone, which had been buried in the gall

(venous injection)

P.O.E. Polyoxethylene

bladder, was confirmed. Nothing unusual was observed in the biliary tract system, liver and other tissues in histochemically.

EXAMPLE 1

In an Erlenmeyer flask, 70 ml of terpinolene and 30 ml of human bile were charged and temperature was controlled to 37°C in a water bath. About 700 mg of human cholesterol stone were added to the mixture and the whole was shaken violently in the water bath. Though terpinolene did not give homogeneous mixture with the bile, disappearance of the human gallstone was recognized within 120 minutes.

In the same manner, disappearance of human gallstones within 120 minutes was recognized when terpinolene was replaced with other monoterpenes including terpinene, menthone, 1,4-cineole, carvone, limonene, 1,8-cineole, piperitone, terpineol, dipentene, citronellal and nerol.

EXAMPLE 2

In an Erlenmeyer flask, 70 ml of farnesol and 30 ml of human bile were charged and temperature was controlled to 37°C in a water bath. About 700 mg of human cholesterol stone were added to the mixture and the whole was shaken violently in the water bath. Though farnesol did not give homogeneous mixture with the bile, disappearance of the human gallstone was recognized within 180 minutes.

In the same manner, disappearance of human gallstones within 180 minutes was recognized when farnesol was replaced with other sesquiterpenes such as nerolidol, bisabolene or zingiberene.

EXAMPLE 3

In an Erlenmeyer flask, 70 ml of caraway oil and 30 ml of human bile were charged and the temperature was controlled to 37°C in a water bath. About 700 mg of human cholesterol stone were added to the mixture and the whole was shaken violently in the water bath. Though caraway oil did not give homogeneous mixture with the bile, disappearance of the human gallstone was recognized within 120 minutes.

In the same manner, disappearance of human gallstones within 120 minutes was recognized when caraway oil was replaced with lemongrass oil, lemon oil, lavender oil, turpentine oil, citronella oil, bergamot oil, eucalyptus oil or ginger oil.

EXAMPLE 4

Twenty milliliters of menthone were added to 1.5 g of sorbitan monooleate and the whole blended thoroughly in a water bath at 50°C. Menthone was added to make the whole quantity 100 ml. After allowing the solution to stand at 5°C for 12 hours, the solution was filtered and the filtrate was further allowed to stand at 5°C for 72 hours. The solution was still stable and phase separation did not occur.

The gallstone solubilizer was shaken together with isotonic sodium chloride solution (as artificial bile) and human bile in a flask to obtain homogeneous mixture. No separation was observed 5 minutes after. The solubilizer exhibited a strong solubilizing effect for human cholesterol stone in bile and the stone was solubilized within 60 minutes.

Similar effects were obtained when sorbitan monooleate was replaced with other nonionic surfactants

such as sorbitan monolaurate, glyceryl monostearate, sorbitan monopalmitate, polyoxyethylene sorbitan monooleate, polyoxyethylene castor oil or polyoxyethylene tristearate.

EXAMPLE 5

Twenty milliliters of dipentene were added to 0.3 g of sorbitan monooleate and 0.2 g of polyoxyethylene sorbitan stearate and the whole was blended thoroughly in a water bath at 50°C. Dipentene was added to make the total 100 ml. After the same procedures as in Example 4, similar effects were obtained.

EXAMPLE 6

0.5 g of polyoxyethylene stearate and 5 g of ethanol were mixed together thoroughly in a water bath at 50°C to obtain solution. Then, limonene was added to the solution under stirring to make the total 100 ml. After allowing the mixture to stand at 5°C for 12 hours, the solution was filtered. The resulting filtrate was thoroughly miscible with human bile. After allowing the solution to stand at 5°C for 72 hours, neither separation nor change in appearance occurred. The solubilizer exhibited a strong solubilizing effect on human cholesterol stone in bile and solubilization time was within 60 minutes.

EXAMPLE 7

Five g of isopropylidene glycerol were added to 1.0 g of sorbitan monolaurate and 0.1 g of ethanol and the whole was blended thoroughly in a water bath at 50°C to obtain homogeneous mixture. Menthone was added under stirring to make the total 100 ml. After allowing the solution at 5°C for 12 hours, the solution was filtered. Thereafter, the same procedures as in Example 6 were repeated to obtain the similar effects.

EXAMPLE 8

Five g of ethanol were added to 0.5 g of polyoxyethylene castor oil and 0.5 g of sorbitan monopalmitate and the whole was blended thoroughly in a water bath at 50°C to obtain a homogeneous mixture. Thereafter, terpinolene was added to the mixture under stirring to make the total 100 ml. After allowing the solution at 5°C for 12 hours, the solution was filtered. Thereafter, the same procedures as in Example 6 were repeated to obtain similar effects.

EXAMPLE 9

Five g of ethanol were added to 0.5 g of polyoxyethylene sorbitan monooleate and 0.5 g of sorbitan sesquioleate. Then bergamot oil was added to the mixture to make the total 100 ml. Thereafter, the same procedures as in Example 6 were repeated to obtain the similar effects.

EXAMPLE 10

0.5 g of lecithin and 5 g of ethanol were added to 0.5 g of polyoxyethylene sorbitan monolaurate and 0.5 g of glyceryl monostearate. Then eucalyptus oil was added to the mixture to make the total 100 ml. Thereafter, the same procedures as in Example 6 were repeated to obtain similar effects.

EXAMPLE 11

50 milliliters of 1,4-cineole were added to 5.0 g of polyoxyethylene castor oil and 3.0 g of water and the

whole was blended thoroughly in a water bath at 35°C to obtain homogeneous mixture. Thereafter, 1,4-cineole was added again to the mixture to make the total 100 ml. After allowing the solution at 5°C for 12 hours, the solution was filtered and the filtrate was allowed to stand at 5°C for 78 hours. It was stable and no phase separation occurred. The thus obtained gallstone solubilizer was shaken together with isotonic sodium chloride solution (as artificial bile) or human bile in a flask to obtain homogeneous mixtures. After five minutes, no separation was observed. The product exhibited a strong solubilizing effect on human gallstones in bile and solubilization time thereof was within 60 minutes.

EXAMPLE 12

20 milliliters of terpinolene were added to a mixture of 0.6 g of sorbitan monooleate, 0.5 g of polyoxyethylene hydrogenated castor oil and 0.1 g of water and the whole was blended thoroughly in a water bath at 50°C to obtain homogeneous mixture. Thereafter, terpinolene was added to the mixture to make the total 100 ml. Thereafter, the same procedures as in Example 11 were repeated to obtain similar effects.

It will be understood that the invention is not limited to the embodiments disclosed above, which are offered illustratively, and that modifications may be made without departing from the invention.

EXAMPLE 13

0.2 g of water were added to 2.8 g of polyoxyethylene sorbitan monooleate having about 20 moles of oxyethylene (Polysorbate 80) and the both was blended thoroughly at room temperature for 10 minutes. Then, 50 ml of limonene was added to the mixture and the whole was blended at room temperature for 15 minutes. An

adequate amount of limonene was added to the solution to make the total volume to 100 ml and the whole was blended at room temperature for 15 minutes.

Thereafter, the same procedures as in Example 11 was repeated to obtain similar effects.

EXAMPLE 14

0.5 g of ethanol were added to 2.5 g of polyoxyethylene sorbitan monooleate having about 20 moles of oxyethylene (Polysorbate 80) and the both was blended thoroughly at room temperature for 10 minutes. Then, 50 ml of limonene was added to the mixture and the whole was blended at room temperature for 15 minutes. An adequate amount of limonene was added to the solution to make the total volume to 100 ml and the whole was blended at room temperature for 15 minutes.

Thereafter, the same procedures as in Example 11 were repeated to obtain similar effects.

What we claim is:

1. A gallstone solubilizer for dissolving cholesterol-type gallstones by direct injection into the affected parts of the patient through a medical cathether, comprising:

- a. 99.8 - 70% (W/V) of limonene;
- b. 0.1 - 15% (W/V) of a member selected from the group consisting of sorbitan monolaurate, sorbitan monooleate and polyoxyethylene sorbitan monooleate having about 20 oxyethylene units; and
- c. 0.1 - 15% (W/V) of a member selected from the group consisting of ethanol and water.

2. A method of eliminating cholesterol-type gallstones comprising infusing into the bile duct of the patient the gallstone solubilizer of claim 1 in an amount sufficient to eliminate the cholesterol-type gallstones.
